MINING MACHINE

Charles F. Osgood, Claremont, N. H., assignor to
 Sullivan Machinery Company, a corporation of
 Massachusetts

Application October 29, 1930, Serial No. 491,971

35 Claims. (Cl. 262—30)

This invention relates to mining machines and more particularly, but not exclusively, to improvements in coal mining machines of the flexibly fed, continuous cutter, bottom cutting type.

An object of this invention is to provide an improved coal mining machine. Another object is to provide an improved coal mining machine of the room and pillar, low-vein type. A further object is to provide an improved flexible feeding means for such a machine whereby the machine may be fed and guided in an improved manner. Another object is to provide an improved coal mining machine of the flexibly fed, continuous cutter, bottom cutting type wherein the driving motor rests directly upon and slides over the mine floor and drives from its forward end the feeding and cutting mechanisms, the feeding mechanism being arranged on the machine in a transverse zone intermediate the motor and cutting mechanism, thereby rendering the machine extremely compact both vertically and longitudinally. A further object is to provide an improved coal mining machine of the room and pillar, low-vein type having improved feeding and guiding mechanism arranged in an improved manner on the machine and wherein separate relatively rotatable power operated and controlled feed operating and controlling members respectively cooperative with separate flexible feeding elements, are employed for feeding and guiding the machine for sliding movement over the mine floor, the said members and the driving mechanism therefor being arranged in an improved manner on the machine whereby the machine is rendered extremely compact. Yet another object is to provide in a flexible feeding means of the aforesaid character improved driving and controlling means for the feed operating and controlling members whereby the latter may be separately or simultaneously driven in a direction to draw in their respective flexible feeding elements at relatively low speed or at relatively high speed and having associated therewith improved control mechanism whereby the said members may rotate in a direction to pay out their respective flexible feeding elements under various degrees of operator-controlled frictional resistance, or without such resistance, as conditions may require. A further object is to provide in such a feeding means, improved mechanism including a separate and distinct fast and slow speed gear train for each member whereby the said members may be rotated in-

dependently in winding direction at either a relatively high speed or a relatively low speed, each gear train for each member having a separate friction controlling clutch whereby either member may be driven at either speed at will. 60 These and other objects and advantages of this invention will, however, hereinafter more fully appear.

In the accompanying drawings there is shown 65 for purposes of illustration one embodiment which the invention may assume in practice.

In these drawings,—

Fig. 1 is a plan view of the illustrative embodiment of the improved mining machine, a part of the machine frame being removed to 70 show a portion of the internal mechanism;

Fig. 2 is a central longitudinally extending vertical sectional view taken substantially on line 2—2 of Fig. 1, with parts shown in elevation. 75

Fig. 3 is a transverse vertical sectional view taken substantially on line 3—3 of Fig. 1; and

Fig. 4 is a transverse vertical sectional view taken substantially on line 4—4 of Fig. 1.

In this illustrative embodiment of the invention there is shown a coal mining machine of the room and pillar, continuous cutter, bottom cutting type having flexible feeding means for feeding and guiding the machine during its movement over the mine floor. The machine generally comprises a machine frame 1 of generally rectangular shape having a smooth plane bottom surface 2 which rests and slides upon the mine floor during operation of the machine. The machine frame consists of a rear motor section 3 and a front cutter and feed section 4, the motor section housing a horizontal motor 5 of a low compact design. Rigidly secured within the front frame section 4 and projecting forwardly lengthwise of the machine is a horizontal plane cutter bar 6 about the outer edges of which an endless cutter bit carrying cutter chain 7 is adapted to be circulated. The top and bottom plane surfaces of the cutter bar 6 lie in horizontal planes intersecting the motor, and the vertical dimension of the motor is only 80 that requisite to its power producing function and substantially determines the height of the machine. Feeding and guiding of the machine are effected by means of relatively rotatable feed operating and controlling members 8 and 9 herein in the form of cable winding or haulage drums, respectively cooperating with flexible feeding elements 10 and 11, herein in the form of cables or ropes. The feed operating and controlling members in the present instance rotate 85 90 95 100 105 110

in opposite directions and are arranged in an improved manner on the machine in coaxial relation with their axes extending transversely of the machine. The feeding mechanism is disposed in a transverse zone between the motor and the cutting mechanism, thereby materially decreasing the length of the machine without increasing the vertical and lateral limits thereof. When the machine is cutting from right to left the feed cable 10 is extended from the bottom of the feed drum 8 around a guide sheave 12 carried by a vertically swingable swing arm 13 supported by a bracket 14 attached to the side of the front frame section 4. The feed cable 10 passes around this guide sheave and extends laterally from the machine to a suitable anchor located adjacent the coal face at the lefthand rib of the room. The controlling cable 11 is extended from beneath the control drum 9 in a rearward direction and passes around horizontal guide sheaves 15 and 16, the latter being carried by a swingable bracket 17 pivoted on the motor frame section 3 about a vertical axis coincident with the axis of the guide sheave 15. The control cable 11 passes around the guide sheave 15 laterally rearwardly from the machine to a suitable anchor located at the right hand rib of the room. When the machine is cutting in the opposite direction, i. e., from left to right, the motor 5 is reversed, the cutter bits turned in their respective links, and the cables are re-wound on the drums and extended from the machine in an opposite manner. A guide sheave 18, similar to the guide sheave 12 and mounted in a similar manner on the machine, is provided for the feed cable during feeding in the left to right direction while horizontal guide sheaves 19 and 20, similar to the guide sheaves 15 and 16, are arranged at the opposite rear corner of the motor frame to guide the control cable during this feeding operation. The swingable brackets for the guide sheaves 16 and 20 are provided with suitable locking means engageable with apertures 21 formed in a bottom ledge 22 integral with the motor frame section for locking the guide sheaves in their innermost portion. Arranged at the longitudinal vertical center of the machine is a horizontal guide sheave 23.

As mentioned above, the motor 5, which may be of the reversible electric type, is of a low compact design and in the present instance has its power shaft 24 horizontally disposed and extending longitudinally of the machine. Fixed to the forward end of the power shaft 24 of the motor is a spur pinion 25 meshing with a spur gear 26 fixed to a shaft 27 arranged in planes above and parallel with the motor shaft and suitably journaled within the front frame section 4. Fixed to the forward end of the shaft 27 is a bevel pinion 28 meshing with a large bevel gear 29 enclosed within the forward end of the frame section 4 and suitably journaled within the frame for rotation about a vertical axis. Bevel gear 29 is connectible by a cutter chain clutch 30, of a usual design, to the hub of a cutter chain drive sprocket 31 which engages and drives the cutter chain 7 in a well-known manner. This chain sprocket is arranged in a chamber 32 extending completely across the machine and arranged between the rear end of the cutter bar 6 and the portion of the frame housing the drive gearing of the feeding mechanism, and this chamber forms a passage for the cuttings brought back from the

kerf by the cutter chain. The cutter chain clutch 30 is provided with usual shipper mechanism including a shipper yoke 33 secured to a transverse operating rod 34 having at its outer ends suitable operating handles 35. It will thus be seen that the cutter chain may be connected in driving relation with the motor 5 or remain idle at will, simply by connecting or releasing clutch 30.

Now referring to the improved driving gearing for the feed operating and controlling members 8 and 9 whereby the latter may be separately or simultaneously rotated in winding direction at either a relatively high or a relatively low speed, it will be noted that secured to the shaft 27 adjacent the spur gear 26 is a worm 36 meshing at its opposite sides with worm wheels 37 and 38 arranged on parallel vertical axes, as clearly shown in Fig. 4, and respectively keyed to parallel vertical shafts 39 and 40 arranged at opposite sides of the longitudinal vertical center of the machine and suitably journaled within the machine frame. A separate and distinct fast and slow predetermined transmission mechanism is provided for each of the drums 8 and 9, and as the structure of each of these transmission mechanisms is substantially identical a detailed description of one will suffice for both. Now referring to the fast and slow predetermined speed driving mechanism between the worm wheel 37 and the feed drum 8, it will be observed that keyed to the lower end of the shaft 39 is a spur gear 41 meshing with a spur gear 42, the gears 41 and 42 rotating in planes adjacent the bottom of the machine and the gear 42 being keyed to a vertical shaft 43 arranged parallel with the shaft 39 and likewise suitably journaled within the front frame section 4. Herein keyed to the vertical shafts 39 and 43 respectively are worms 44 and 45, the worm 44 having teeth of steeper lead than the teeth of the worm 45; the worm 45 being a slow speed driving worm while the worm 44 is a high speed driving worm. The worm 44 meshes with a fast speed worm wheel 46, while the worm 45 meshes with a slow speed worm wheel 47; these worm wheels being arranged in coaxial relation on a horizontal axis extending transversely of the machine, and in the present instance, parallel with the axis of the drum 8. These worm wheels are suitably journaled in ball bearings supported in a suitable manner within the machine frame and have mounted centrally therewith a shaft 48 likewise journaled in ball bearings. This shaft 48 has fixed thereto at its outer end a spur gear 49 meshing with an internal gear 50 herein formed integral with the feed drum 8. The worm wheels 46 and 47 are selectively connectible to the shaft 48 by means of multiple disc clutches 51, 52 respectively. The operating means for the clutches 51, 52 comprises an axially shiftable clutch applying member 53 mounted on the adjacent hubs of the worm wheels and slidable in opposite directions to effect application of one clutch or the other. The means for sliding the clutch applying member 53 consists of a shipper yoke 54 pivoted at 55 within the machine frame and having a forwardly projecting lever portion 56 extending within a notch or recess 57 formed in a transversely movable horizontal actuating rod 58. The means for shifting the rod 58 back and forth to effect swinging of the shipper yoke about its pivot consists of a rotatable nut 59 connected to the threaded end 60 of the rod.

The means for turning the nut consists of miter gears 61 actuated by a rod 62 extending longitudinally rearwardly of the machine and having a suitable operating handle 63 conveniently arranged at the rear end of the motor frame section 3. It will thus be seen that when clutch 51 is applied and clutch 52 released the winding drum 8 may be driven in winding direction at a relatively high speed through spur gearing 25, 26, worm gearing 36, 37, vertical shaft 39, worm gearing 44, 46, shaft 48 and the spur gear 49 meshing with the internal gear 50 secured to the drum. It will also be seen that when clutch 51 is released and clutch 52 applied the winding drum 8 may be driven in winding direction at a relatively slow speed through the reduction gearing 41, 42 and worm gearing 45, 47.

As previously mentioned, the transmission mechanism for the winding drum 9 is substantially identical to that for the winding drum 8 and consists of fast and slow speed worms 65 and 66 meshing with worm wheels 67 and 68 respectively, these worm wheels being arranged in coaxial relation on horizontal axes aligned with the axes of the worm wheels 46, 47. These worm wheels are connectible by similar multiple disc clutches 69 and 70 respectively in driving relation with the winding drum 9. The clutches 69 and 70 have operating mechanism similar to the operating mechanism for the clutches 51 and 52 and including a clutch applying member 71, shipper yoke 72, rod 73 for swinging the shipper yoke, miter gears 74 and rod 75 extending rearwardly of the machine and having an operating handle 76. These worm wheels are selectively connectible by the clutches 69 and 70 to a coaxial shaft 77 having secured thereto at its outer end a spur gear 78 meshing with an internal gear 79, herein formed integral with the drum 9. When one of the friction clutches 69, 70 is applied and the other released, the drum 9 may be rotated in winding direction at either a relatively high speed or a relatively low speed, depending upon which one of the clutches is applied.

Both of the drums 8 and 9 are journaled upon the machine frame in a similar manner, and, as shown in Fig. 3, the drums are each journaled on ball bearings 80 and 81 arranged within a chamber 82 formed within the drum and supported by a stub shaft 83 formed integral with a plate 84 suitably attached to the vertical side wall of the front frame section 4. The internal gear is secured to the drum by bolts 85 and dowel pins 86 and the drum and gear are retained on the shaft 83 by means of suitable retaining means 87.

It will be noted that the drums may rotate separately or simultaneously in winding direction at relatively low speed or at relatively high speed and that the friction clutches may be so released as to permit the drums to rotate in unwinding direction under various degrees of frictional resistance. Upon full release of the clutches the drums may rotate freely. Various modes of operation of the improved machine will be clearly apparent to those skilled in the art, and as the method of use of a room and pillar mining machine is well known, further description of the operation of the machine is thought unnecessary.

As a result of this improved arrangement of the feeding mechanism on the machine, it will be observed that an extremely low, compara-

tively short, compact machine is produced and one which is accordingly adapted to use in even the lowest commercially workable veins of coal. Furthermore, this improved construction enables an extremely compact machine to be obtained wherein the length thereof is reduced to a minimum while still retaining the low compact motor construction, the improved feeding mechanism and the novel compact arrangement of the driving gearing and feed drums on the machine reducing the dimensions of the machine to a minimum. Furthermore by arranging the feed and controlling drums in the novel manner disclosed, and by providing the improved arrangement of the transmission mechanism for driving the drums, the machine is not only rendered extremely compact but is also exceedingly flexible in operation and easy to handle, especially during the various maneuverings of the machine to position the same to effect its sumping, transverse, and withdrawal cuts in accordance with the room and pillar system of mining. It will also be noted that the improved feeding mechanism is extremely well balanced and symmetrical in design, the driving mechanisms for the drums being substantially identical in construction, thereby reducing the number of different parts with the resultant decrease in the cost of manufacture and replacement. These and other uses and advantages of the improved mining machine will be clearly apparent to those skilled in the art.

While there is in this application specifically described one form which this invention may assume in practice, it will be understood that this form of the same is shown for purposes of illustration and that the invention may be modified and embodied in various other forms without departing from its spirit or the scope of the appended claims.

What I claim as new and desire to secure by Letters Patent is:

1. In a mining machine, a rearwardly located horizontal motor having its casing resting directly upon and slidable in any direction over the mine floor and its power shaft extending longitudinally of the machine, the vertical dimension of said motor being only that requisite to its power producing function and substantially determining the height of the machine, cutting mechanism driven from the forward end of said motor power shaft including a forwardly projecting cutter bar, and feeding mechanism driven from the forward end of said motor power shaft including relatively rotatable feed operating and controlling members disposed on horizontal axes at opposite sides of the machine and each adapted to cooperate directly with flexible feeding means, and mechanism for rotating said members either separately or simultaneously at similar fast and slow speeds in a direction to draw in their respective flexible feeding means including a separate and distinct fast and slow speed transmission mechanism for each member and all the elements of each transmission mechanism rotating on fixed axes during drive at either speed.

2. In a mining machine, a rearwardly located horizontal motor having its casing resting directly upon and slidable in any direction over the mine floor and its power shaft extending longitudinally of the machine, the vertical dimension of said motor being only that requisite to its power producing function and substantially determining the height of the machine,

- cutting mechanism driven from the forward end of said motor power shaft including a forwardly projecting cutter bar, and feeding mechanism driven from the forward end of said motor power shaft including relatively rotatable feed operating and controlling members arranged in coaxial relation on horizontal axes in advance of the motor and each adapted to cooperate directly with flexible feeding means, and mechanism for 10 rotating said members either separately or simultaneously at similar fast and slow speeds in a direction to draw in their respective flexible feeding means including a separate and distinct fast and slow speed transmission mechanism for each member and all the elements of each transmission mechanism rotating on fixed axes during drive at either speed.
3. In a mining machine, a rearwardly located horizontal motor having its casing resting directly upon and slideable in any direction over the mine floor and its power shaft extending longitudinally of the machine, the vertical dimension of said motor being only that requisite to its power producing function and substantially determining the height of the machine, cutting mechanism driven from the forward end of said motor power shaft including a forwardly projecting cutter bar, and feeding mechanism driven from the forward end of said motor power shaft including relatively rotatable feed operating and controlling members arranged in coaxial relation on horizontal axes extending transversely of the machine, and each adapted to cooperate directly with flexible feeding means, and mechanism for 25 rotating said members either separately or simultaneously at similar fast and slow speeds in a direction to draw in their respective flexible feeding means including a separate and distinct fast and slow speed transmission mechanism for each member and all the elements of each transmission mechanism rotating on fixed axes during drive at either speed.
4. In a mining machine, a machine frame adapted to rest upon and slide in any direction over the mine floor, a horizontal motor carried at the rear end of said frame and having its power shaft extending longitudinally of the machine, cutting mechanism driven from the forward end of said motor power shaft including a forwardly projecting cutter bar, and feeding mechanism driven from the forward end of said power shaft including relatively rotatable feed operating and controlling members arranged on 30 horizontal axes at opposite sides of the machine and each adapted to cooperate directly with flexible feeding means, and mechanism for rotating said members either separately or simultaneously at similar fast and slow speeds in a direction to draw in their respective flexible feeding means including a separate and distinct fast and slow speed transmission mechanism for each member and all the elements of each transmission mechanism rotating on fixed axes during drive at either speed.
5. In a mining machine, a machine frame adapted to rest upon and slide in any direction over the mine floor, a horizontal motor carried at the rear end of said frame and having its power shaft extending longitudinally of the machine, cutting mechanism driven from the forward end of said power shaft including a forwardly projecting cutter bar, and feeding mechanism driven from the forward end of said power shaft including relatively rotatable feed 40 operating and controlling members arranged on horizontal axes extending transversely of the machine and each adapted to cooperate directly with flexible feeding means, and mechanism for rotating said members either separately or simultaneously at similar fast and slow speeds in a direction to draw in their respective flexible feeding means including a separate and distinct fast and slow speed transmission mechanism for each member and all the elements of each transmission mechanism rotating on fixed axes during drive at either speed.
6. A mining machine adapted to be moved laterally along the face of a mine wall comprising a motor contained in a casing adapted to rest directly upon the mine floor, said machine having a cutter carrying end, a feed driving mechanism disposed between the cutter carrying end of the machine and the motor casing and included substantially within the vertical limits thereof, said feed driving mechanism including a plurality of variable speed transmission devices all of the elements of which rotate on fixed axes during drive at any speed, a pair of feed drums disposed on transverse axes, one driven through 45 one transmission device and the other driven through the other device, said drums driven through said transmission devices at similar speeds, and means for selectively engaging either of said feed drums with their respective variable speed devices.
7. In a low vein room and pillar mining machine, a horizontal motor having its axis extending longitudinally of the machine and comprising a low compact frame housing power producing means and providing a smooth bottom surface slidably engageable with the mine floor during cutting, the vertical dimension of said motor frame being substantially only that requisite to the power producing function of the 50 motor and substantially determining the height of the machine, kerf cutting mechanism driven from the forward end of said motor and including a kerf cutter projecting forwardly lengthwise of the machine during lateral cutting, and feeding means driven from the forward end of said motor and disposed wholly within the vertical limits thereof, said feeding means including a plurality of relatively rotatable feed 55 operating and controlling members each adapted to cooperate directly with flexible feeding means and disposed on horizontal axes at opposite sides of the machine, and driving and controlling mechanism for said members for effecting rotation of said members either separately or simultaneously in a direction to draw in said flexible feeding means at relatively low speed or at relatively high speed and including a fast and slow speed transmission mechanism for each member whereby one member may be rotated at 60 a low speed while said other member is rotated simultaneously at a high speed and vice versa, each transmission mechanism including a fast speed friction controlling clutch and a slow speed friction controlling clutch.
8. In a low vein room and pillar mining machine, a horizontal motor having its axis extending longitudinally of the machine and comprising a low compact frame housing power producing means and providing a smooth bottom surface slidably engageable with the mine floor during cutting, the vertical dimension of said motor frame being substantially only that requisite to the power producing function of the 65 motor and substantially determining the height

- of the machine, kerf cutting mechanism driven from the forward end of said motor and including a kerf cutter projecting forwardly lengthwise of the machine during lateral cutting, and feeding means driven from the forward end of said motor and disposed wholly within the vertical limits thereof, said feeding means including a plurality of relatively rotatable feed operating and controlling members each adapted to cooperate directly with flexible feeding means and disposed on horizontal axes at opposite sides of the machine and driving and controlling mechanism for said members for effecting rotation of said members either separately or simultaneously in a direction to draw in said flexible feeding means at relatively low speed or at relatively high speed or to permit said members to rotate in a direction to pay out said flexible feeding means under various degrees of frictional resistance, and including a fast and slow speed transmission mechanism for each member whereby one member may be rotated at a low speed while said other member is rotated simultaneously at a high speed and vice versa, each transmission mechanism including a fast speed friction controlling clutch and a slow speed friction controlling clutch. 9. In a lowvein room and pillar mining machine, a horizontal motor having its axis extending longitudinally of the machine and comprising a low, compact frame housing power producing means and providing a smooth bottom surface slidably engageable with the mine floor during cutting, the vertical dimension of said motor frame being substantially only that requisite to the power producing function of the motor and substantially determining the height of the machine, kerf cutting mechanism driven from the forward end of said motor and including a kerf cutter projecting forwardly lengthwise of the machine during lateral cutting, and feeding means driven from the forward end of said motor and disposed wholly within the vertical limits thereof, said feeding means including a plurality of relatively rotatable feed operating and controlling members each adapted to cooperate directly with flexible feeding means and disposed on horizontal axes at opposite sides of the machine, and driving and controlling mechanism for said members for effecting rotation of said members either separately or simultaneously in a direction to draw in said flexible feeding means at relatively low speed or at relatively high speed or to permit said members to rotate in a direction to pay out said flexible feeding means under various degrees of frictional resistance or to permit said members to rotate in a direction to pay out said flexible feeding means without such frictional resistance, and including a fast and slow speed transmission mechanism for each member whereby one member may be rotated at a low speed while said other member is rotated simultaneously at a high speed and vice versa, each transmission mechanism including a fast speed friction controlling clutch and a slow speed friction controlling clutch. 10. In a mining machine, a rearwardly located horizontal motor having its casing resting directly upon and slidable in any direction over the mine floor and its power shaft extending longitudinally of the machine, the vertical dimension of said motor being only that requisite to its power producing function and substantially determining the height of the machine, cutting mechanism driven from the forward end of said motor power shaft including a forwardly projecting kerf cutter, and feeding mechanism driven from the forward end of said motor power shaft including relatively rotatable feed operating and controlling members disposed on horizontal axes in advance of the motor and each adapted to cooperate directly with flexible feeding means, and mechanism for effecting rotation of said members either separately or simultaneously at similar fast and slow speeds including for each member fast and slow predetermined speed transmission mechanism through which it, but not the other member, is driven and all the elements of each transmission mechanism rotating on fixed axes during drive at either speed. 11. In a mining machine, a rearwardly located horizontal motor having its casing resting directly upon and slidable in any direction over the mine floor and its power shaft extending longitudinally of the machine, the vertical dimension of said motor being only that requisite to its power producing function and substantially determining the height of the machine, cutting mechanism driven from the forward end of said motor power shaft including a forwardly projecting kerf cutter, and feeding mechanism driven from the forward end of said motor power shaft including relatively rotatable feed operating and controlling members disposed on horizontal axes in advance of the motor and each adapted to cooperate directly with flexible feeding means, and mechanism for effecting rotation of said members either separately or simultaneously at similar fast and slow speeds including for each member fast and slow predetermined speed transmission mechanism through which it, but not the other member, is driven and all the elements of each transmission mechanism rotating on fixed axes during drive at either speed. 12. In a mining machine, a rearwardly located horizontal motor having its casing resting directly upon and slidable in any direction over the mine floor and its power shaft extending longitudinally of the machine, the vertical dimension of said motor being only that requisite to its power producing function and substantially determining the height of the machine, cutting mechanism driven from the forward end of said motor power shaft including a forwardly projecting kerf cutter, and feeding mechanism driven from the forward end of said motor power shaft including relatively rotatable feed operating and controlling members disposed on horizontal axes extending transversely of the machine and each adapted to cooperate directly with flexible feeding means, and mechanism for effecting rotation of said members either separately or simultaneously at similar fast and slow speeds including for each member fast and slow predetermined speed transmission mechanism through which it, but not the other member, is driven and all the elements of each transmission mechanism rotating on fixed axes during drive at either speed. 13. In a mining machine, a rearwardly located horizontal motor having its casing resting directly upon and slidable in any direction over the mine floor and its power shaft extending longitudinally of the machine, the vertical dimension of said motor being only that requisite to its power producing function and substantially determining the height of the machine, cutting mechanism driven from the forward end of said motor power shaft including a forwardly projecting kerf cutter, and feeding mechanism driven from the forward end of said motor power shaft including relatively rotatable feed operating and controlling members disposed on horizontal axes in advance of the motor and each adapted to cooperate directly with flexible feeding means, and mechanism for effecting rotation of said members either separately or simultaneously at similar fast and slow speeds including for each member fast and slow predetermined speed transmission mechanism through which it, but not the other member, is driven and all the elements of each transmission mechanism rotating on fixed axes during drive at either speed.

- mechanism driven from the forward end of said motor power shaft including a forwardly projecting kerf cutter, and feeding mechanism driven from the forward end of said motor power shaft including relatively rotatable feed operating and controlling members arranged on horizontal axes extending transversely of the machine and each adapted to cooperate directly with flexible feeding means, and mechanism for effecting rotation of said members either separately or simultaneously at relatively low speed or at relatively high speed including for each member fast and slow predetermined speed transmission mechanism through which it, but not the other member, is driven, each transmission mechanism including a fast speed worm gear train and a slow speed worm gear train.
14. In a mining machine, a rearwardly located horizontal motor having its casing resting directly upon and slideable in any direction over the mine floor and its power shaft extending longitudinally of the machine, the vertical dimension of said motor being only that requisite to its power producing function and substantially determining the height of the machine, cutting mechanism driven from the forward end of said motor power shaft including a forwardly projecting kerf cutter, and feeding mechanism driven from the forward end of said motor power shaft including relatively rotatable feed operating and controlling members arranged on horizontal axes extending transversely of the machine and each adapted to cooperate directly with flexible feeding means, and mechanism for effecting rotation of said members either separately or simultaneously in a direction to draw in their respective flexible feeding means at relatively low speed or at relatively high speed including for each member fast and slow predetermined speed transmission mechanism through which it, but not the other member, is driven, each transmission mechanism including a fast speed worm gear train and a slow speed worm gear train, and control mechanism included in each transmission mechanism to permit each member to rotate in a direction to pay out its flexible feeding means under various degrees of frictional resistance or without such resistance.
15. In a mining machine, a rearwardly located horizontal motor having its casing resting directly upon and slideable in any direction over the mine floor and its power shaft extending longitudinally of the machine, the vertical dimension of said motor being only that requisite to its power producing function and substantially determining the height of the machine, cutting mechanism driven from the forward end of said motor power shaft including a forwardly projecting cutter bar, and feeding mechanism driven from the forward end of said power shaft including relatively rotatable feed operating and controlling members arranged on horizontal axes at opposite sides of the machine and each adapted to cooperate directly with flexible feeding means, and mechanism for rotating said members either separately or simultaneously in a direction to draw in their respective flexible feeding means at relatively low speed or at relatively high speed including a separate and distinct fast and slow speed transmission mechanism for each member, each transmission mechanism including a transverse shaft operatively connected to its respective member, and fast and slow speed worm wheels coaxial with said shaft and connectible thereto.
16. In a mining machine, a rearwardly located horizontal motor having its casing resting directly upon and slideable in any direction over the mine floor and its power shaft extending longitudinally of the machine, the vertical dimension of said motor being only that requisite to its power producing function and substantially determining the height of the machine, cutting mechanism driven from the forward end of said motor power shaft including a forwardly projecting kerf cutter, and feeding mechanism driven from the forward end of said power shaft including relatively rotatable feed operating and controlling members arranged on horizontal axes extending transversely of the machine and each adapted to cooperate directly with flexible feeding means, and mechanism for effecting rotation of said members either separately or simultaneously in a direction to draw in their respective flexible feeding means at relatively low speed or at relatively high speed including for each member fast and slow predetermined speed transmission mechanism through which it, but not the other member, is driven, each transmission mechanism including a fast speed worm gear train and a slow speed worm gear train, and control mechanism included in each transmission mechanism to permit each member to rotate in a direction to pay out its flexible feeding means under various degrees of frictional resistance or without such resistance.
17. In a mining machine, a machine frame adapted to rest upon and slide in any direction over the mine floor, a horizontal motor carried at the rear end of said frame and having its power shaft extending longitudinally of the machine, cutting mechanism driven from the forward end of said motor power shaft including a forwardly projecting cutter bar, and feeding mechanism driven from the forward end of said power shaft including relatively rotatable feed operating and controlling members arranged on horizontal axes at opposite sides of the machine and each adapted to cooperate directly with flexible feeding means, and mechanism for rotating said members either separately or simultaneously in a direction to draw in their respective flexible feeding means at relatively low speed or at relatively high speed including a separate and distinct fast and slow speed transmission mechanism for each member, each transmission mechanism including a transverse shaft operatively connected to its respective member, and fast and slow speed worm wheels coaxial with said shaft and connectible thereto.
18. In a mining machine, a machine frame adapted to rest upon and slide in any direction over the mine floor, a horizontal motor carried at the rear end of said frame and having its power shaft extending longitudinally of the machine, cutting mechanism driven from the forward end of said motor power shaft including a forwardly projecting cutter bar, and feeding mechanism driven from the forward end of said power shaft including relatively rotatable feed operating and controlling members arranged on horizontal axes at opposite sides of the machine and each adapted to cooperate directly with flexible feeding means, and mechanism for rotating said members either separately or simultaneously in a direction to draw in their respective flexible feeding means at relatively low speed or at relatively high speed including a separate and distinct fast and slow speed transmission mechanism for each member, each transmission

mechanism including a transverse shaft operatively connected to its respective member, and fast and slow speed worm wheels coaxial with said shaft and connectible thereto, and worms meshing with said worm wheels respectively and rotating on parallel axes.

19. In a mining machine, a machine frame adapted to rest upon and slide in any direction over the mine floor, a horizontal motor carried at the rear end of said frame and having its power shaft extending longitudinally of the machine, cutting mechanism driven from the forward end of said motor power shaft including a forwardly projecting cutter bar, and feeding mechanism driven from the forward end of said power shaft including relatively rotatable feed operating and controlling members arranged on horizontal axes at opposite sides of the machine and each adapted to cooperate directly with flexible feeding means, and mechanism for rotating said members either separately or simultaneously in a direction to draw in their respective flexible feeding means at relatively low speed or at relatively high speed including a separate and distinct fast and slow speed transmission mechanism for each member, each transmission mechanism including a transverse shaft operatively connected to its respective member, and fast and slow speed worm wheels coaxial with said shaft and connectible thereto, and worms meshing with said worm wheels respectively and rotating on parallel vertical axes.

20. In a mining machine, a machine frame adapted to rest upon and slide in any direction over the mine floor, a horizontal motor carried at the rear end of said frame and having its power shaft extending longitudinally of the machine, cutting mechanism driven from the forward end of said power shaft including a forwardly projecting cutter bar, and cutter driving means including a horizontal shaft extending longitudinally of the machine, and feeding means driven from the forward end of said motor power shaft including relatively rotatable feeding members arranged on horizontal axes at opposite sides of the machine and each adapted to cooperate directly with flexible feeding means, and mechanism operatively connected to said longitudinally extending shaft for rotating said members either separately or simultaneously at similar fast and slow speeds in a direction to draw in their respective flexible feeding means including a separate and distinct fast and slow speed transmission mechanism for each member, all the elements of each transmission mechanism rotating on fixed axes during drive at either speed.

21. In a mining machine, a machine frame adapted to rest upon and slide in any direction over the mine floor, a horizontal motor carried at the rear end of said frame and having its power shaft extending longitudinally of the machine, cutting mechanism driven from the forward end of said power shaft including a forwardly projecting cutter bar, and cutter driving means including a horizontal shaft extending longitudinally of the machine, and feeding means driven from the forward end of said motor power shaft including relatively rotatable feeding members arranged on horizontal axes at opposite sides of the machine and each adapted to cooperate directly with flexible feeding means, and mechanism operatively connected to said longitudinally extending shaft for rotating said members either separately or simultaneously at similar fast and slow speeds in a direction to draw in their respective flexible feeding means including a separate and distinct fast and slow speed transmission mechanism for each member, and a common driving element fixed to said longitudinally extending shaft between the motor and the cutter driving means and through which both of said transmission mechanisms are driven.

22. In a mining machine, a machine frame adapted to rest upon and slide in any direction over the mine floor, a horizontal motor carried at the rear end of said frame and having its power shaft extending longitudinally of the machine, cutting mechanism driven from the forward end of said power shaft including a forwardly projecting cutter bar, and cutter driving means including a horizontal shaft extending longitudinally of the machine, and feeding means driven from the forward end of said motor power shaft including relatively rotatable feeding members arranged on horizontal axes at opposite sides of the machine and each adapted to cooperate directly with flexible feeding means, and mechanism operatively connected to said longitudinally extending shaft for rotating said members either separately or simultaneously in a direction to draw in their respective flexible feeding means at relatively low speed or at relatively high speed including a separate and distinct fast and slow speed transmission mechanism for each member, said transmission mechanisms each including a gear element and said gear elements meshing with a gear element fixed to said longitudinally extending shaft.

23. In a mining machine, a rearwardly located horizontal motor having its casing resting directly upon and slideable in any direction over the mine floor and its power shaft extending longitudinally of the machine, the vertical dimension of said motor being only that requisite to its power producing function and substantially determining the height of the machine, cutting mechanism driven from the forward end of said motor power shaft including a forwardly projecting cutter bar, and cutter driving means including a horizontal shaft extending longitudinally of the machine, and feeding mechanism driven from said longitudinally extending cutter driving shaft including relatively rotatable feed operating and controlling members disposed on horizontal axes at opposite sides of the machine and each adapted to cooperate directly with flexible feeding means, and mechanism for rotating said members either separately or simultaneously at similar fast and slow speeds in a direction to draw in their respective flexible feeding means including a separate and distinct fast and slow speed transmission mechanism for each member, and a common driving element fixed to said longitudinally extending shaft between the motor and the cutter driving means and through which both of said transmission mechanisms are driven.

24. In a mining machine, a machine frame adapted to rest upon and slide in any direction over the mine floor, a horizontal motor carried at the rear end of said frame and having its power shaft extending longitudinally of the machine, cutting mechanism driven from the forward end of said motor power shaft including a separate and distinct fast and slow speed transmission mechanism for each member, and a common driving element fixed to said longitudinally extending shaft between the motor and the cutter driving means and through which both of said transmission mechanisms are driven.

- ward end of said motor power shaft including a forwardly projecting cutter bar, and feeding means driven from the forward end of said power shaft including relatively rotatable feed operating and controlling members arranged at the forward end of the machine, and plural speed driving means for said members including separate fast and slow speed gear trains for each member, said four gear trains including four final transmission gears coaxially arranged on axes extending transversely of the machine in advance of said motor. 5
31. In a mining machine, a machine frame adapted to rest upon and slide in any direction over the mine floor, a horizontal motor carried at the rear end of said frame and having its power shaft extending longitudinally of the machine, cutting mechanism driven from the forward end of said motor power shaft including a forwardly projecting cutter bar, and feeding means driven from the forward end of said power shaft including relatively rotatable feed operating and controlling members arranged at the forward end of the machine, and plural speed driving means for said members including separate fast and slow speed gear trains for each member, said four gear trains including four final transmission gears coaxially arranged on axes extending transversely of the machine in advance of said motor and a separate friction controlling clutch for each gear. 10
32. In a mining machine, a machine frame adapted to rest upon and slide in any direction over the mine floor, a horizontal motor carried at the rear end of said frame and having its power shaft extending longitudinally of the machine, cutting mechanism driven from the forward end of said motor power shaft including a forwardly projecting cutter bar, and feeding means driven from the forward end of said power shaft including relatively rotatable feed operating and controlling members arranged at the forward end of the machine in advance of said motor on axes parallel to a vertical plane extending transversely of the machine, and separate and distinct fast and slow speed transmission means for each member each including a horizontal drive shaft, said shafts arranged in axial alignment, and driving connections between each of said shafts and its respective member, said members being driven at either speed through said shafts and all the elements of said transmission means rotating on fixed axes during drive at either speed. 15
33. In a mining machine, a machine frame adapted to rest upon and slide in any direction over the mine floor, a horizontal motor carried at the rear end of said frame and having its power shaft extending longitudinally of the machine, cutting mechanism driven from the forward end of said motor power shaft including a forwardly projecting cutter bar, and feeding means driven from the forward end of said power shaft including relatively rotatable feed operating and controlling members arranged at the forward end of the machine in advance of said motor, and a separate and distinct plural speed transmission mechanism for each member whereby said members may be rotated either separately or simultaneously at relatively high speed or at relatively low speed and including fast and slow speed terminal gears for each transmission mechanism, a terminal gear of one transmission mechanism arranged coaxially with a terminal gear of said other mechanism, and manually controllable friction controlling clutches, one individual to each terminal gear, for connecting said members in driving relation with their respective terminal gears. 20
34. In a mining machine, a machine frame adapted to rest upon and slide in any direction over the mine floor, a horizontal motor carried at the rear end of said frame and having its power shaft extending longitudinally of the machine, cutting mechanism driven from the forward end of said motor power shaft including a forwardly projecting cutter bar, and feeding means driven from the forward end of said power shaft including relatively rotatable feed operating and controlling members arranged at the forward end of the machine in advance of said motor, and a separate and distinct plural speed transmission mechanism for each member whereby said members may be rotated either separately or simultaneously at relatively high speed or at relatively low speed, said transmission mechanisms including aligned shafts, driving connections between said shafts and said members, respectively, a fast speed gear train and a slow speed gear train for each shaft having fast and slow speed terminal gears, and connections between said gears and their respective shafts. 25
35. In a mining machine, a machine frame adapted to rest upon and slide in any direction over the mine floor, a horizontal motor carried at the rear end of said frame and having its power shaft extending longitudinally of the machine, cutting mechanism driven from the forward end of said motor power shaft including a forwardly projecting cutter bar, and feeding means driven from the forward end of said power shaft including relatively rotatable feed operating and controlling members arranged at the forward end of the machine in advance of said motor, and driving means for said members including aligned shafts one for each member, driving connections between said members and their respective shafts, and a separate and distinct fast and slow speed worm gear train for each shaft including a fast speed worm wheel and a slow speed worm wheel, said worm wheels arranged coaxially with said shafts. 30
